UNITED STATES PATENT OFFICE.

THEODORE C. VERMILYE, OF ONTARIO, AND DAVID BLAIKIE HISLOP, OF UPLAND,
CALIFORNIA.

DESIGN FOR A HEATER.

45,439.

Specification for Design.

Patented Mar. 17, 1914.

Application filed July 2, 1913. Serial No. 777,089. Term of patent 7 years.

To all whom it may concern:

Be it known that we, THEODORE C. VERMILYE, a citizen of the United States, residing at Ontario, in the county of San Bernardino and State of California, and DAVID BLAIKIE HISLOP, a subject of the King of the United Kingdom of Great Britain and Ireland, residing at Upland, in the county of San Bernardino and State of California, have invented a new, original, and ornamental Design for Heaters, of which the following is a specification, reference being had to the

accompanying drawing, forming a part thereof.

The figure is a side elevation of the heater showing our new design.

We claim:

The ornamental design for a heater as shown.

THEODORE C. VERMILYE.
DAVID BLAIKIE HISLOP.

Witnesses:

G. B. HARDING,
GEO. N. KNOX.
